UNITED STATES PATENT OFFICE.

PAUL R. HIGGINBOTHAM, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

LIFTING DEVICE FOR DEMOUNTABLE WHEELS.

Application filed March 10, 1922. Serial No. 542,723.

To all whom it may concern:

Be it known that I, PAUL R. HIGGINBOTHAM, a citizen of the United States, residing at Philadelphia, Pennsylvania, have 5 invented certain new and useful Improvements in Lifting Devices for Demountable Wheels, of which I declare the following to be a full, clear, and exact description.

My invention relates to an improved lifting device for demountable wheels and has 10 to do, more particularly, with an improved device or tool for lifting demountable disc wheels from the ground to the spare wheel carrier or dummy hub.

15 Spare disc wheels are usually carried on a dummy hub, secured to the rear end of the automobile body at some little distance above the ground, and the removal of a spare wheel from this hub or carrier, or the lifting 20 of a spare wheel up to such carrier, is attended with some difficulty due to the fact that the wheel is rather heavy and does not offer any convenient hand-hold for use in grasping the wheel. The principal object 25 of my invention is to provide a simple tool or device to facilitate the lifting of a demountable disc wheel from the ground to the carrier or the lowering of such a wheel from the carrier to the ground. Another 30 object of my invention is to provide a tool or device which gives the operator a mechanical advantage in lifting or lowering a demountable disc wheel to or from the carrier and which also affords a convenient 35 means for handling and controlling such disc wheel during the lifting or lowering movement. A further object of my invention is to provide a tool having the advantageous features described above, which may 40 be folded in a very compact space so that it may be conveniently stored in the automobile. A further object of my invention is to provide a tool having the advantages set forth above and which may be very 45 quickly and easily applied in position for use in raising or lowering the demountable disc wheel to or from the carrier. A further object of my invention is to provide a very simple and easily manipulated tool, for raising 50 or lowering a demountable disc wheel to or from the wheel carrier, which may be constructed very cheaply and economically.

Further objects, and objects relating to 55 details and economies of operation and construction, will definitely appear from the

detailed description to follow. In one instance, I accomplish the objects of my invention by the devices and means described in the following specification. My invention is clearly defined and pointed out in the 60 appended claims. A structure constituting a preferred embodiment of my invention is illustrated in the accompanying drawings, forming a part of this specification, in which:

65 Fig. 1 is a view of the rear end of an automobile in side elevation, showing a disc wheel carrier and the disc wheel thereon in section, and illustrating the application of my tool for use in lowering the disc wheel from the carrier to the ground. The position of the disc wheel and the tool, when the wheel has been lowered to the ground, is shown in dotted lines.

70 Fig. 2 is a detail, sectional view of a portion of the carrier, wheel and tool, taken on line 2-2 of Fig. 4.

75 Fig. 3 is a view similar to Fig. 1, but showing in full lines, the wheel and tool in lowered position, and, in dotted lines, in an intermediate position.

80 Fig. 4 is a view of the carrier in front elevation, taken on the line 4-4 of Fig. 3.

85 Fig. 5 is a view similar to Fig. 2, showing the wheel hanging freely on the notched supporting pin of the carrier, ready to be lifted therefrom by the tool.

90 Fig. 6 is a plan view of the wheel lifting tool, and

95 Fig. 7 is a plan view of the tool folded for storage.

In the drawings, the same reference numerals refer to the same parts throughout the several views and the sectional view is taken looking in the direction of the arrows at the ends of the section lines.

100 In general, my invention consists in providing a lever which is fulcrumed on a swinging or floating link detachably connected to or carried on the spare wheel carrier, or some other fixed support on the automobile. I prefer to provide the dummy hub or spare wheel carrier with a transverse bar or portion, over which one end of the floating link may be hooked, the other end 105 of said floating link being pivotally connected to the lever. For convenience in storage and handling, I prefer to make the lever in two sections, which are jointed so that they may be folded together. It has been 110

proposed, heretofore, to use a plain lever, which may be made of two sections jointed together, so as to give a mechanical advantage in raising or lowering a demountable disc wheel. In all such cases, however, it has been proposed to provide a fixed fulcrum for the lever and the result has been that a very small mechanical advantage is obtained when the movement of the lever 10 is confined within the range, which is practicable. According to my invention, I substitute a shifting fulcrum for such a lever, in place of the fixed fulcrum heretofore employed, and this enables me to get the desired mechanical advantage in lifting the wheel, without having to swing the end of the lever through such a large range of movement.

Referring to the numbered parts of the drawing, I have shown the rear end of an automobile body, 10, upon which a spare wheel carrier or dummy hub, 11, is supported by the braces or brackets, 12. This carrier or dummy hub is designed to carry the demountable disc wheel, 13, which has a central opening and a marginal flange, 14, around said opening. The tool or lifting device works through this central opening in the disc wheel and engages this flange. Arranged at equal distances from the center of the wheel, around this central opening, are a plurality of perforated sockets, 15, through which the threaded studs, 16, on the carrier, extend. The disc wheel is held in place on the carrier by conical nuts, 17, screwed on such studs and projecting into said sockets. At the upper portion of the carrier, instead of a threaded stud, 16, a stud, or post, 18, is provided, extending through the corresponding perforated socket of the disc and provided with a hook or notch, 19, in its upper edge. When the various nuts, 17, are removed from the threaded studs, 16, the wheel may be gently pulled forward until it hangs suspended on this stud, 18, being prevented from slipping therefrom by the notch, 19. The stud, 18, may be perforated, at 20, to receive the shackle of a padlock for locking the disc 50 wheel on the carrier. The carrier, 11, is provided with a vertical slot, 21, extending upwardly from the lower edge thereof, through which the tool or lifting lever works. A transverse bar, 22, is secured to the rear face of the carrier in such position that it bridges the upper part of the slot, 21. My improved lifting device or tool includes a link, 23, the upper portion of which is formed into a hook, 24. The opposite end 60 of said link is pivotally connected by the pin, 25, to one end of a lever section, 26. The opposite end of said lever section, 26, has the upper edge thereof formed into a notch or hook, 27, which is adapted to receive the flange, 14, of the disc wheel in

lifting or lowering the wheel to or from the carrier. Said end of the lever section, 26, is pivotally connected by the pin, 28, to the outer or handle section, 29, of the lever, and the latter has a laterally projecting ear, 30, at the rear end, which is adapted to overlap and engage the upper edge of the lever section, 26, in the rear of the hook, 27.

It will be seen that the lever made up of the two sections, 26 and 29, is fulcrumed on the floating link, 23, at the point, 25. The load is applied to the lever at the hook, 27, and power is applied to the forward end of the handle. When the forward end of the handle is moved upwardly to lift a load resting on the hook, 27, the lever section, 29, turns on the pivot, 28, until the ear, 30, engages the edge of the lever section, 26, and, thereafter, the two sections move together as a single lever having its fulcrum at the point, 25. The use of the two sections jointed together to form the lever gives very long lever arms so that it is possible to secure a considerable mechanical advantage in lifting the wheel and it permits the folding of the sections into very compact space when the tool is to be stored and carried in the car. It is to be noted that the fulcrum for this lever is not fixed but floats, as the link, 23, swings around its support on the transverse bar, 22, of the carrier. This gives a floating or shifting fulcrum for the lever and, consequently, I am able to secure the desired mechanical advantage in lifting the wheel without the need of so great a range of movement of the handle of the tool, as would be the case if the fulcrum were fixed. Furthermore, this gives greater flexibility in manipulating the wheel, in that it does not need to be located each time at the same distance from the carrier in order to insert the tool in proper relationship for lifting the wheel from the ground to the dummy hub. The floating link, 23, thus enables one to use the tool without bringing the spare wheel to a definite fixed point on the ground with relation to the carrier, before applying the tool to lift the wheel.

In Fig. 1, the disc wheel is shown upon the spare wheel carrier or dummy hub, 11. If one desires to release the wheel and lower it to the ground, the nuts, 17, are removed, and the wheel is pulled gently forward until the edge of the perforation in the upper socket, 15, rests in the notch, 19, of the stud, 18, and the wheel is suspended freely on said pin or stud. The link, 23, is swung to a position in which it lies alongside of the section, 26, of the lever and the pivotally connected ends of said link and lever section are inserted through the central opening in the disc and through the slot, 21, of the carrier, 11, and passed therethrough until the hook, 24, engages the

- transverse bar, 22, on the carrier, so that the floating link is anchored at its upper end. The user now grasps the handle section, 29, of the lever and lifts the same until the 5 hook, 27, engages the flange, 14, surrounding the central opening in the disc wheel. A slight lift on the handle of the lever is sufficient to dislodge the wheel from the pin or stud, 18, and the wheel is transferred by 10 this movement from its support on the carrier to its support on the hook, 27, of the lever, on which it hangs freely in a vertical position. The operator now lowers the wheel to the ground by means of the lever, 15 which turns on the pivot, 25, during the lowering operation. The floating fulcrum link, 23, may also swing on its pivotal support on the bar, 22, during the lowering operation, so as to facilitate the landing of 20 the wheel on the ground in the desired position. The handle section, 29, of the lever, may be withdrawn through the central opening in the disc and the wheel rolled away. In lifting a wheel from the ground 25 to the carrier, the wheel is held by the operator upright upon the ground, somewhat in the rear of the carrier, and the hook, 24, of the floating fulcrum link is hooked over the transverse bar, 22, of the carrier, 11. 30 The operator then passes the handle section, 29, of the tool through the central opening in the disc wheel until the hook, 27, engages the flange, 14, surrounding said central opening. The operator now lifts on the end 35 of the handle section, 29, of the lever and thus raises the wheel, at the same time swinging it toward the carrier, such action being facilitated by the swinging fulcrum link, 23. The operator raises the wheel and 40 moves it toward the carrier until the stud, 18, passes through the proper perforated socket, 15, of the disc wheel, whereupon he lowers the lever slightly, allowing the disc 45 wheel to hang upon the stud, 18. The lever can now be removed through the slot, 21, and the central opening of the disc and the wheel securely fastened in place by screwing the nuts, 17, on the threaded studs, 16, and, if desired, passing the shackle of a padlock 50 through the opening, 20, of the stud, 18. When not in use, the lifting tool may be folded very compactly, as shown in Fig. 6, for storage in the automobile.
- I am aware that the lifting device, which 55 I have disclosed in this specification, may be altered considerably without departing from the spirit of my invention and, therefore, I claim my invention broadly, as indicated by the appended claims.
- Having thus described my invention, what 60 I claim as new and useful and desire to secure by Letters Patent is:
1. A lifting device for demountable wheels comprising a lever insertable through 65 the central aperture of the wheel and means
- providing a shifting fulcrum for said lever.
2. A lifting device for demountable wheels comprising a lever insertable through the central aperture of the wheel and means, carried by the spare wheel carrier, and providing a shifting fulcrum for said lever. 70
3. A lifting device for demountable wheels comprising a lever insertable through the central aperture of the wheel and a swinging link pivotally connected to one end of said lever and detachably connected to a fixed support. 75
4. A device for lifting demountable wheels into carrying position on a spare wheel carrier, comprising a lever insertable through the central aperture of the wheel and a swinging link pivotally connected to one end of said lever and having a detachable and pivotal connection with a fixed support on said carrier. 80
5. A device for lifting demountable wheels into carrying position on a spare wheel carrier, comprising a lever insertable through the central aperture of the wheel and a swinging link pivotally connected to one end of said lever and having, at its opposite end, a hook adapted to be detachably connected with a fixed support on said carrier. 85
6. A device for lifting demountable wheels into carrying position on a spare wheel carrier, comprising a lever insertable through the central aperture of the wheel, and having one edge formed to provide a seat for that portion of the wheel at the upper edge of the central aperture therein, and means providing a shifting fulcrum for said lever. 90
7. A device for lifting demountable wheels into carrying position on a spare wheel carrier, comprising a lever insertable through the central aperture of the wheel, and having one edge formed to provide a seat for that portion of the wheel at the upper edge of the central aperture therein, and a member pivotally connected to said carrier and providing a shifting fulcrum for said lever. 100
8. A device for lifting demountable wheels into carrying position on a spare wheel carrier, comprising a lever insertable through the central aperture of the wheel, and having one edge formed to provide a seat for that portion of the wheel at the upper edge of the central aperture therein, and a link pivotally connected to one end of said lever and provided with a hook by means of which it may be detachably and pivotally connected to a fixed support on said carrier. 115
9. A device for lifting demountable wheels into carrying position on a spare wheel carrier, comprising a lever insertable through the central aperture of the wheel and including two lever sections pivotally connected to 120
- 130

gether, one of said sections having a seat for that portion of the wheel at the upper edge of the central aperture therein, and a link pivotally connected to said lever section and provided with a hook adapted to be detachably and pivotally connected to a fixed support on the carrier.

10. The combination with a carrier for demountable wheels provided with a vertical slot and a cross member bridging said slot, of a device for lifting demountable wheels comprising a lever insertable through the central aperture of the wheel and working in said slot and a link detachably and pivotally connected with said cross mem-

ber and providing a shifting fulcrum for said lever.

11. The combination with a carrier for demountable wheels provided with a vertical slot and a cross bar bridging said slot, 20 of a device for lifting demountable wheels comprising a lever insertable through the central aperture of the wheel and working in said slot and a link pivotally connected to one end of said lever and provided with 25 a hook adapted to be detachably engaged with said cross bar.

In testimony whereof, I affix my signature.

PAUL R. HIGGINBOTHAM.
